[57] CLAIM

The ornamental design for a novelty cage, as shown and
described.

DESCRIPTION

FIG. 1 is a perspective view of a novelty cage showing
my new design as viewed looking down from above
towards the right hand front corner thereof;

FIG. 2 is a front elevational view thereof;

FIG. 3 is a rear elevational view thereof;

FIG. 4 is a top plan view thereof;

FIG. 5 is a left-end elevational view thereof; and

FIG. 6 is a right-end elevational view thereof.

The bottom is identical to the top.
